UNITED STATES PATENT OFFICE.

DOUGLAS F. MINER, OF WILKINSBURG, PENNSYLVANIA, ASSIGNOR TO WESTINGHOUSE ELECTRIC & MANUFACTURING COMPANY, A CORPORATION OF PENNSYLVANIA.

BUS BAR.

Application filed September 17, 1920. Serial No. 410,896.

To all whom it may concern:

Be it known that I, DOUGLAS F. MINER, a citizen of the United States, and a resident of Wilkinsburg, in the county of Allegheny and State of Pennsylvania, have invented a new and useful Improvement in Bus Bars, of which the following is a specification.

My invention relates to electrical conductors and particularly to bus-bars for switch-board structures.

The object of my invention is to provide means for attachment to, or for association with, conductors in a manner to compensate for the skin effect thereof to effect, thereby, a more uniform distribution of current therethrough, eliminate undue heating and utilize the conductor effectively and economically.

When alternating current passes through a conductor, an alternately expanding and contracting magnetic field is created in and around the conductor. This field induces a counter-electromotive force in the conductor which produces what is known as skin effect. The apparent resistance of a given conductor to alternating current divided by its resistance to direct current, is known as the skin-effect ratio for the particular conditions and the frequency of the alternating current considered. With alternating currents of relatively high values, the skin effect causes the outer portions of a conductor to carry a greater amount of current than the center portion, resulting in undue heating and in an inefficient and uneconomical use of material.

In practicing my invention, I provide conductors and magnetizable members associated in parallel relation thereto to so redistribute the magnetic field of the conductor as to compensate for the skin effect thereof, thus eliminating undue heating and permitting the effective and economical use of conducting material.

In my copending application, Serial No. 412529, filed Sept. 24, 1920, is disclosed a structure for accomplishing results similar to those herein set forth by forming the conductors in a special manner and without the use of magnetizable members as herein described. Other devices appertaining to the distribution of current in conductors are set forth in my copending applications, Serial No. 412530, filed Sept. 24, 1920, and Serial No. 412531, filed Sept. 24, 1920, and in a co-

pending application of C. F. Wagner, Serial No. 412461, filed Sept. 24, 1920.

Figure 1 of the accompanying drawings is a cross-sectional view of a bus-bar of usual form combined with a diagram showing the distribution of current therein.

Fig. 2 is a sectional perspective view of a portion of a bus-bar embodying my invention, and

Fig. 3 is a diagram, showing, by dotted and full-line curves, respectively, a comparison between the curve of Fig. 1 and a curve representing the distribution of current in a bus-bar constructed in accordance with the device illustrated in Fig. 2.

In Fig. 1, a bus-bar 1 of usual form is so affected by alternating current as to cause a greater amount of current to flow along the edges of the conductor than along the center portion thereof. The approximate distribution of current is represented by a curve 2 on a diagram 3, the current values of which, as indicated in the diagram, increase in a direction toward the edges of the conductor. When a conductor is affected in this manner, it is not being utilized in an effective and economical manner, inasmuch as the heating at the edges thereof due to the greater flow of current at these parts, which must be taken into consideration in the design of a switchboard or other supporting structure therefor, is excessive for the amount of copper used and the current desired.

To obviate this condition, the conductor 4 of Fig. 2 may be provided along its edges with magnetizable members 5, preferably of iron or steel and constructed of substantially channel shape, and mounted on, or adjacent to, the conductor in any suitable manner. As shown, the members 5 are disposed on the conductor 4 along the edges 6 thereof and have portions 7 engaging the sides of the conductor and projecting toward the center of the latter. This construction will so increase the reactance of the outer elements 100 of the conductor as to redistribute the current as indicated by a curve 8 in Fig. 3.

This redistribution of the current is accounted for by the fact that, when iron or magnetic substance is placed near a conductor carrying current, it redistributes the magnetic field surrounding the conductor, the flux lines being distorted to pass through

the iron which affords a path of least resistance. The most concentrated portion of the field is near the iron, and because the iron is disposed adjacent the edges of the conductor, the number of flux lines passing through the conductor adjacent the conductor is increased.

The concentration of flux at the outer edges of the conductor induces a counter electromotive force in the neighboring elements thereof. The effect is an increase in the apparent resistance or reactance of the outermost elements of the conductor. The current is limited or opposed more in the outer elements of the conductor than in the central portion thereof, resulting in equalization of the current distribution. The areas under the curves 2 and 8 are equal for the same total current but inasmuch as the root mean square value of current in the conductor 4 is less than that in the conductor 1, the heating in the conductor 4 will be less.

While the total voltage drop over a given length of a conductor having compensating means thereon is greater than an uncompensated conductor of the same shape and length, it is apparent from a study of the current curves above referred to that the permissible current may be increased without increasing the temperature above that of the uncompensated conductor carrying a considerably lower amount of current.

It has been found in actual practice that considerably more current can be carried by a conductor compensated in the manner described than can be carried by an uncompensated conductor of equal shape for a given temperature rise. It is apparent, therefore, that a compensated conductor may serve to carry current with the same temperature rise that has heretofore required a conductor of greater proportions. It will be seen that, by reason of this fact, considerable saving of copper is accomplished in large installations.

By varying the sizes, shapes, proportions and relation of the conductor 4 and the members 5, substantially any desired dis-

tribution of current in the conductor may be obtained.

While I have shown and described a particular form of my invention, changes may be effected therein without departing from the spirit and scope thereof, as set forth in the appended claims.

I claim as my invention:

1. A conductor having a non-circular cross-section and means for compensating the skin effect thereof comprising inductive means disposed adjacent the points in the conductor normally carrying more current than other points thereof.

2. A conductor having a non-circular cross-section and magnetic means disposed adjacent the point in the conductor normally carrying more current than other points thereof for compensating the skin effect thereof.

3. An elongated conductor having a non-circular cross-section and a magnetic metal member disposed thereon adjacent a point normally carrying more current than other portions thereof and in parallel relation thereto to compensate the skin effect thereof.

4. An elongated conductor having a non-circular cross-section and an elongated magnetic metal member embracing the conductor adjacent a point carrying more current than other portions thereof and extending in parallel relation thereto to compensate the skin effect thereof.

5. An elongated conductor and a plurality of magnetic metal members disposed on opposite sides of and parallel to the conductor to compensate the skin effect thereof.

6. A conductor of substantially strap formation and magnetic metal members embracing the opposite edges thereof to compensate for skin effect in the conductor.

7. A bus-bar and magnetizable members of substantially channel-shape embracing the opposite edges thereof.

In testimony whereof, I have hereunto subscribed my name this 11th day of September 1920.

DOUGLAS F. MINER.
